INVALID LIFT

Daniel F. Vanderlyn, Ellenville, and Jay N. Vanderlyn, Kingston, N. Y.; Tracey S. Vanderlyn, executor of the estate of Daniel F. Vanderlyn, deceased

Application June 16, 1944, Serial No. 540,624

6 Claims. (Cl. 5—88)

1

This invention relates to an invalid lift for raising part or all of a patient's body from his bed and temporarily supporting it in elevated position.

An object of the invention is to provide a simple, practical and effective device of the above mentioned kind.

Another object of the invention is to provide a simple form of lift which is portable and may be readily moved from bed to bed as required.

Another object of the invention is to provide a lift comprising a number of flexible supporting bands with means for either elevating all of the bands simultaneously, or individually and selectively.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is an end elevation of a device embodying our invention;

Figure 2 is a side elevation of the device shown in Figure 1;

Figure 3 is a perspective view of the device shown in Figures 1 and 2;

Figure 4 is a detail view, partly in cross section, of a demountable connection between a vertical frame member and a horizontal frame member, taken on the line 4—4 of Figure 5;

Figure 5 is a view showing the members of Figure 4 as seen looking from the right hand side of Figure 4;

Figure 6 is a detail view showing a demountable connection between a transverse frame member and a longitudinally extending frame member;

Figure 7 is a front elevational view, partly in cross section, of means for controlling the length, and therefore the height, of the supporting bands, individually or all together;

Figure 8 is a vertical cross sectional view of one of the several means shown in Figure 7 for winding the supporting bands and thereby controlling their lengths;

Figure 9 is a perspective view of a collar constituting part of the assembly for controlling the lengths of the supporting bands; and

2

Figure 10 is a perspective view of another collar constituting part of the assembly for controlling the lengths of the supporting bands.

As illustrated herein a demountable and readily portable frame is provided, having two ends, and detachable means interconnecting the ends. One of said ends comprises the vertical members 10 and 11, Figure 3, and the transverse members 12 and 13, and the other of said ends comprises the vertical members 14 and 15 and the transverse members 16 and 17. Interconnecting the vertical members 10 and 14, and 11 and 15, respectively, are members 18 and 19, each being provided at its extremities with the caps c adapted to fit over the upper ends of said vertical members. Brackets 20 and 21 are provided intermediate the ends of cross members 13 and 17 respectively, and demountably supported in said brackets is the interconnecting member 22. Preferably cross members 13 and 17 are positioned sufficiently near the lower ends of the vertical supports 10 and 11, and 14 and 15 to permit interconnecting member 22 to extend under a bed or the like when the frame is assembled so that the ends of the frame may be positioned on opposite sides of the bed, and with the interconnecting members 18 and 19 extending over the bed and at a sufficient elevation so that they do not interfere with the raising of a patient from the bed by the means to be described.

Vertical support members 14 and 15 are provided, respectively, with the horizontally aligned brackets 23 and 24 having the bosses or trunnions 25 and 26, respectively, through which the cross bar 27 extends, and in which bar 27 is rotatably supported. Adjacent one end of bar 27, on an end portion thereof projecting outwardly from vertical frame member 15 as shown, Figures 1 and 2, is a gear 28, and in operative relation to gear 28, the worm gear 29 is provided, mounted on the crank arm 30, rotatably supported in casing 31. As shown casing 31, enclosing both gear 28 and worm gear 29, may be integral with bracket 24, on vertical support member 15, and journaled at 32 and 33 to receive and provide bearings for crank 30. By operation of crank arm 30 the bar 27 may thus be rotated in either direction.

Mounted on bar 27 are a number of pairs of collars, each pair comprising the collars 34 (34a in the case of the left hand pair of collars nearest vertical support 14) and 35, and a separate collar 34b positioned adjacent vertical support 15, said collars having annular flange or bearing portions 36 and 37 respectively projecting toward one another. Collars 34, 34a and 34b are keyed to rotat-

able bar 27 as by pins 29, while collars 35 are freely rotatable on bar 27 and are free to slide axially of bar 27 together with the sleeve member with which they are respectively associated as will be described. The collars 34 and 34b are provided with male clutch faces 38, and the collars 35 are provided with the female clutch faces 39, the said clutch faces being of greater diameter than said bearing portion, thus forming the shoulders 40 and 41 respectively. Supported on the bearing portions 36 and 37 of said pairs of collars, respectively, between the said shoulders 40 and 41 thereof, are the sleeves 42. Intermediate each of said sleeves 42 and the rotatable bar 27 the coil springs 43 are provided, the ends of said springs abutting against the ends of the bearing portions 36 and 37 of the collar members 34 and 35, respectively associated with a given sleeve 42, and tending to separate them axially along bar 27. As illustrated each of said sleeves 42 is keyed to the collar member 35 with which it is associated by means of a U-shaped member 44 so that said collar members and said sleeves are slideable together along bar 27. The longer arm 45 of each member 44 is inserted through the bore 46 in sleeve 42 and is screwed into the threaded bore 47 in the flanged portion 37 of clutch member 35, thus joining sleeve 42 to collar member 35, and the shorter arm 48 of the U-shaped member is inserted into the bore 49 adjacent the other end of the sleeve, and is secured therein, as by peening, welding or the like.

Since as stated above the collar 34a and the collars 34 are fixed on the rotatable bar 27, and the sleeves 42 are not keyed either to bar 27 or to said collars 34a and 34 respectively, the sleeves 42 together with their respective collars 35 are movable axially of bar 27 relative to said collar member 34a and 34 respectively. The length of the flanged portion 36 of each of collar members 34a and 34 is proportioned so that its associated sleeve 42 and collar 35 may slide a substantial distance axially of bar 27, toward vertical support 14, against the force of the spring member 43 interposed between each of said pairs of collars 34a and 35, and 34 and 35 respectively. As illustrated (Figure 7) three sets of sleeves 42 and associated collars are shown. Collar 34a nearest vertical support 14, and its sleeve 42 and collar 35 are identified in Figure 7 as winder unit 1, and the two sets comprising collars 34 and 35 and their sleeves 42 and associated collars 35, are identified as winder units 2 and 3. It will be seen that the sleeve 42 and associated collar 35 of unit 1 may be moved axially of bar 27 relatively to collar 34a, and that similarly the sleeves 42 of units 2 and 3 and their associated collars 35 may be moved axially of bar 27 relative to the respective collars 34 of said units.

It will be noted that the collar 34a, which is nearest to vertical support 14, and collar 34b, which is adjacent to vertical support member 15, being both keyed to bar 27, and thus fixed in position, serve to prevent withdrawal of bar 27 from the trunnions 25 and 26.

It will thus be seen that due to the expanding action of the springs 43, the female clutch face of collar 35 of each winder unit will be urged into engagement with the male clutch face of collar 34 of the next winder unit, except that the clutch face of collar 35 of winder unit 3 will be urged into engagement with the male clutch face of separate collar 34b, thus interconnecting all of the said winding units 1, 2 and 3, and thus joining all of said units to rotatable

bar 27. And it will be understood that the sleeve 42 and collar 35 of each unit may be moved axially of bar 27, in the direction of vertical support 14 against the action of the unit's spring 43, within the distance separating the shoulder of the fixed collar (34a of unit 1, and 34 of unit 2 or 3) from the adjacent end of its associated sleeve 42. Thus the sleeve 42 and collar 35 of unit 1 may be moved away and disconnected from collar 34 of unit 2, and individually rotated, and similarly the sleeve 42 and collar 35 of unit 2 may be moved away and disconnected from collar 34 of unit 3, and the sleeve 42 and collar 35 of unit 3 may be moved away and disconnected from collar 34b, so that the sleeve 42 of each of said units is disengageable and is freely and individually rotatable on bar 27.

A number of supporting bands 50 of any strong flexible material, such for example as webbing, which if desired may be faced with material such as cotton or canvas, are fixed at one end to the cross member 51, which as illustrated herein is removably mounted in one frame end above transverse frame member 12 (as for example by the means illustrated in Figures 4 and 5) and are preferably led over the cross member 52, which as illustrated herein is removably mounted in the other frame end, above the transverse frame member 16, extending between the vertical supports 14 and 15. The bands 50 are festooned between the members 51 and 52 forming loops so that changes in the length of the bands due to winding up or unwinding of the bands will effect substantial changes in the height of the loops with a minimum of lateral displacement of the loops. The bands 50, in use, are wound around the sleeves 42 rotatably mounted on bar 27 as described above, after they have been drawn under the patient to be elevated, between the surface of the bed and the portion or portions of the patient's body it is desired to elevate.

The bent over arms 45 and 48 of the U-shaped members 44 are of a length such that the body portions of said members respectively are spaced radially outward from the sleeves 42 on which they are respectively mounted, thus providing spaces or openings through which the free ends of the bands 50 respectively may be initially inserted and facilitating the wrapping or winding of the bands around said sleeves respectively, and serving to prevent slipping of the bands on the sleeves.

By the means provided all of the bands 50 may be wound on their respective sleeves 42 in unison and to the same degree, or, if it is desired as is often the case, to elevate one or more of the bands more than others of the bands, this may be accomplished by disconnecting one unit from the abutting units and winding it manually to adjust the length and height of a given band as desired.

As illustrated herein the vertical members 10 and 11 and 14 and 15 respectively are provided at their lower ends respectively with casters 51 so that the assembled lift may be readily moved from one room to another, and from one bed to another bed in the same or different rooms. Preferably the casters are provided with known locking means for preventing accidental moving of the lift, as when it is in use.

To summarize, the device as shown herein comprises three separate winding sleeves 42 mounted on a rotatable bar 27. In Figure 7 these winders or sleeves are identified generally as 1, 2, and 3, reading from left to right. It will be noted that

No. 1 winder or winding sleeve 42 is slidable in the direction of collar member 34a over its laterally extending annular flange 36, and that this movement of the winder or winding sleeve 42 carries collar 35 and U-shaped member 44 of the No. 1 winding assembly out of engagement with collar 34 and male faced clutch 38 of the No. 2 winding assembly. Accordingly winder or winding sleeve 42 of No. 1 assembly is now unclutched from the rotatable bar 27 and is free to be turned manually. By so doing one can remove supporting band 50 from winder or winding sleeve 42 of winder assembly No. 1 in Figure 7, or wind it up further on sleeve 42. Similarly by unclutching winder No. 2 from winder assembly 3 one can leave winder unit No. 3 clutched to the crank shaft 27 through its engagement with collar 34b which is keyed to the crank shaft or rotatable bar 27. If winder units 1 and 2 are manually held unclutched, winder unit 3 may be operated alone by rotation of crank 30.

By unclutching winder unit No. 1, described as above and manually holding it out of engagement and turning crank 30, winders 2 and 3 may be operated simultaneously without winding unit No. 1, and by leaving all of the winder units engaged to their fixed clutch members respectively, as shown in Figure 7, all three of the winders will be operated together when the rotatable shaft 27 is rotated.

We have described above selective winding by operation of rotatable arm 27. In such operation of course only the winders which are left clutched to rotatable rod 27 are rotated.

The winders can also be rotated individually by hand, and to accomplish this it is simply necessary to unclutch one of the winding units from the others and turn it by hand, until the strap or band 50 for that unit has been wound up sufficiently. The unclutched winder unit is then released and the action of spring 43 immediately returns it into engagement with its associated fixed clutch member 34.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What we claim is:

1. A portable invalid lift comprising a plurality of end support members, side bars joining said end support means spaced apart a distance permitting said support means to be positioned on opposite sides of a bed or the like, each of said support means comprising a fixed transversely extending bar, and one of said support means comprising a rotatable transverse bar positioned below the said fixed transverse bar, said rotatable bar having thereon a number of sleeves rotatable around said bar as an axis, manually disengageable clutch means individual to each of said sleeves for connecting said sleeves respectively with said rotatable bar for rotation therewith, and supporting bands fixed at one end to the transverse bar of one of said end supports and extending over the fixed transverse bar of the other of said end supports and having their free

ends respectively wound around said sleeves, whereby said bands may be elevated or lowered in unison when all the sleeves are clutched to said rotatable bar and said bar is rotated or selectively when one or more of said collars is disconnected from said rotatable bar, each of said sleeves having a U-shaped arm secured to the sleeve at its respective ends but spaced from the sleeve in a radial direction intermediate its ends providing an elongated space adapted to receive the free end of one of said supporting bands and to prevent slipping of the band on the sleeve as the band is wound upon said sleeve.

2. An invalid lift comprising a frame movable into a position straddling a bed, a number of flexible supporting bands supported in said frame so that they form loops extending transversely of the bed, and means for modifying the length of said loops selectively or in unison, said means comprising a bar rotatably supported in said frame, a number of sleeves mounted on said bar in axial relation, and individually rotatable with respect to said bar, said bands being wound on said sleeves respectively, clutch members equal in number to said sleeves, fixed to said bar at spaced intervals and in alternate arrangement with said sleeves, clutch means carried by each of said sleeves and engageable with said fixed clutch members respectively, means individual to each sleeve urging its clutch means into engagement with one of the said clutch members fixed to said bar, there being sufficient space between successive fixed clutch members to permit each sleeve to be manually moved axially along said bar to disengage its clutch means from its associated fixed clutch member whereupon said sleeve may be manually rotated about said bar.

3. An invalid lift comprising a frame movable into a position straddling a bed, a number of flexible supporting bands supported in said frame so that they form loops extending transversely of the bed, and means for modifying the length of said loops selectively or in unison, said means comprising a bar rotatably mounted in said frame, a plurality of clutch members fixed on said bar in spaced relation, each of said members comprising an annular bearing portion having at one end a collar of greater diameter than said bearing portion, a number of sleeves loosely mounted on said bar and positioned in alternate arrangement with said fixed clutch members, with one end of each sleeve extending over the said annular bearing portion of one of said fixed clutch members as a bearing, and having clutch means at its opposite end adapted to engage the clutch means of the adjacent fixed clutch member, said fixed clutch members being spaced apart sufficiently to permit each of said sleeves to be moved axially along said bar sufficiently to move out of engagement with its fixed clutch member, whereupon it may be rotated around said bar as an axis, and means serving to urge each of said sleeves into engagement with its fixed clutch member, whereby, when said sleeves are each clutched to their respective fixed clutch members they may be rotated in unison by rotation of said bar.

4. A portable lift comprising end support members spaced apart a predetermined distance by demountable connecting rails, a number of supporting bands attached respectively at one end to one of said support members, a rotatable bar supported on the other of said support members, means for rotating said rotatable bar, a number of pairs of collars positioned on said bar each

collar of each pair having an annular flange extending in the direction of the other collar of the pair, the collars of each pair having dissimilar, oppositely disposed clutch faces, one collar of each pair being fixed to the bar and the other collar of each pair being freely rotatable on said bar, and a number of sleeves, equal in number to said pairs of collars, each of said sleeves being rotatably mounted on said bar between the collars of one of said pairs of collars and extending over the flanges of said collars respectively and interengaged with the rotatable collar of its pair of collars for rotation therewith about said bar, and for sliding movement therewith axially along said bar, the said fixed collars being sufficiently spaced apart to permit each sleeve and its said movable collar to which it is attached to be moved sufficiently to disengage the clutch face of its said movable collar from the clutch face of the fixed collar of the adjoining pair of collars, and spring means extending between the collars of each pair of collars tending to move the said movable collar of the pair, together with the sleeve which is attached to said movable collar, into engagement with the fixed clutch member of the adjoining pair of collars, whereby each of said sleeves may be rotated in unison with the said bar as a common driving means, or alternatively an individual sleeve may be manually disengaged from its fixed collar and rotated independently of the bar and of the other sleeves to selectively raise or lower a particular band.

5. An invalid lift comprising a frame, a number of supporting bands fixedly supported at one end in said frame, a rotatable bar, means for rotating said bar, a number of winder units mounted on said bar each of said units comprising, a collar fixed to the bar and having a clutch face, a sleeve on which one of said supporting bands may be wound said sleeve being loosely mounted on said bar and having at its end opposite to said fixed collar a clutch face complementary to the clutch face of the fixed collar of the adjoining unit, said winder units being disposed in end to end relation on said bar

with the clutch face of the sleeve of one winder unit being opposed to the fixed clutch member of the adjoining unit, and means tending to push the clutch face of the sleeve into engagement with the fixed clutch member of the next unit, the said fixed collars being spaced apart sufficiently to permit each sleeve to be moved axially of the bar sufficiently to disengage its clutch face from the fixed clutch of the next unit, whereby each winder unit may be disengaged from each other winder unit and thus also disengaged from said rotatable bar.

6. An invalid lift comprising a frame, a number of bands fixedly supported on one side of said frame, a bar rotatably mounted on the other side of said frame, means for rotating said bar, a number of clutch members fixed on said bar at spaced intervals, a number of sleeves loosely mounted on said bar alternately with said fixed clutch members and adapted to receive and engage the free ends of said bands respectively, each sleeve having at one end a clutch member adapted to engage one of said fixed clutch members, and yielding means urging each sleeve to move axially of said bar to engage its said clutch end with the adjacent fixed clutch, said fixed collars being spaced apart a sufficient distance relative to the length of said sleeves to permit each sleeve to be moved axially along said rod sufficiently to disengage its said clutch face from said adjacent fixed clutch member.
